a corporation of New York

Application July 12, 1949, Serial No. 3,847

Term of patent 14 years

(Cl. D74—24)

To all whom it may concern:

Be it known that I, Louis Bodor, a citizen of the United States of America, residing at Munsey Park, Long Island, county of Queens, and State of New York, have invented a new, original, and ornamental Design for a Combined Pencil Holder and Multiplier, of which the following is a specification, reference being had to the accompanying drawing, forming part thereof.

In the drawing:

Fig. 1 is an elevational view of a combined pencil holder and multiplier, showing my new design.

Fig. 2 is a top plan view thereof.

Fig. 3 is a bottom plan view thereof.

The broken line showings are for illustrative purposes only.

I claim:

The ornamental design for a combined pencil holder and multiplier, as shown and described.

LOUIS BODOR.
